(57) **ABSTRACT**

A portable case is for power accessories including wires. The portable case includes a housing having first and second sides, first and second ends extending between the first and second sides, and dividing walls extending between one or more of the first and second sides and the first and second ends. The dividing walls define compartments. The housing also includes floor panels respectively within the compartments. The portable case also includes aligned slot pairs carried by the dividing walls, and spindles respectively received by the aligned slot pairs, each spindle configured to receive a wire.

20 Claims, 7 Drawing Sheets

PORABLE CASE WITH SPINDLES FOR ACCESSORIES AND RELATED METHODS

TECHNICAL FIELD

The present disclosure relates to the field of electrical devices, and, more particularly, to an accessory case for electrical accessories and related methods.

BACKGROUND

Electronic devices are ubiquitous in modern society. Even though most common portable electronic devices are battery powered, these portable electronic devices usually include a charging cable and associated charger power block. Because of this, most households accumulate a large number of different cables and charger power blocks, which are commonly stored in unorganized fashion, making finding the right cable/charger block difficult.

Since most users store their cables and charger power blocks in an unorganized fashion, many users resort to purchasing new cables and charger power blocks even when they are unneeded. This approach leads to user frustration, more e-waste, and increased costs for the user.

SUMMARY

Generally, a portable case is for a plurality of power accessories comprising a plurality of wires. The portable case comprises a housing comprising first and second sides, first and second ends extending between the first and second sides, and a plurality of dividing walls extending between at least one of the first and second sides and the first and second ends. The plurality of dividing walls (i.e., fixed dividing walls) defines a plurality of compartments. The housing also includes a plurality of floor panels respectively within the plurality of compartments. The portable case also includes a plurality of aligned slot pairs carried by the plurality of dividing walls, and a plurality of spindles respectively received by the plurality of aligned slot pairs, each spindle configured to receive a wire from the plurality of wires. Respective slots from each slot pair are carried on opposite sides of a given compartment. Each spindle is respectively received by a respective aligned slot pair.

In some embodiments, the plurality of power accessories may include a charger power block, and at least one floor panel from the plurality of floor panels may comprise a plurality of spaced apart slot pairs. The charger power block may be received by a respective spaced apart slot pair. The plurality of aligned slot pairs may comprise a first set of aligned slot pairs and a second set of aligned slot pairs. Each first aligned slot pair may be spaced apart a first distance, and each second aligned slot pair may be spaced apart a second distance less than the first distance.

Additionally, the plurality of spindles may comprise a first set of spindles and a second set of spindles different from the first set of spindles. Each first spindle may comprise a first spindle body, a handle portion extending upward from the first spindle body, and a plurality of first spindle slots about a periphery of the first spindle body. The plurality of first spindle slots may comprise a first pair of spindle slots, and at least one second pair of spindle slots having a different shape than the first pair of spindle slots. Each second spindle may include a second spindle body, and a plurality of second spindle slots extending inwardly from a side of the second spindle body. Each second spindle slot may comprise a plurality of curved recess pairs.

Also, the portable case may include a cover carried by the first side and configured to cover the plurality of compartments. The portable case further may include a battery testing device carried within a respective compartment.

Another aspect is directed to a method for making a portable case for a plurality of power accessories comprising a plurality of wires. The method includes forming a housing. The housing comprises first and second sides, first and second ends extending between the first and second sides, and a plurality of dividing walls extending between at least one of the first and second sides and the first and second ends. The plurality of dividing walls defines a plurality of compartments. The housing further comprises a plurality of floor panels respectively within the plurality of compartments. The method also includes coupling a plurality of aligned slot pairs to be carried by the plurality of dividing walls, and coupling a plurality of spindles to be respectively received by the plurality of aligned slot pairs, each spindle configured to receive a wire from the plurality of wires.

BRIEF DESCRIPTION OF THE DRAWINGS

FIG. 1 is a perspective view of a portable case without a cover and with wires and a charging block, according to the present disclosure.

FIG. 2 is a perspective view of the portable case from FIG. 1.

FIG. 3 is another perspective view of the portable case from FIG. 1 without the cover.

FIG. 4 is a top plan view of the portable case from FIG. 1 without the cover.

FIG. 5 is a perspective view of a first spindle from the portable case of FIG. 1.

FIG. 6 is a front plan view of the first spindle from the portable case of FIG. 1.

FIG. 7 is a perspective view of a second spindle from the portable case of FIG. 1.

DETAILED DESCRIPTION

The present disclosure will now be described more fully hereinafter with reference to the accompanying drawings, in which several embodiments of the invention are shown. This present disclosure may, however, be embodied in many different forms and should not be construed as limited to the embodiments set forth herein. Rather, these embodiments are provided so that this disclosure will be thorough and complete, and will fully convey the scope of the present disclosure to those skilled in the art. Like numbers refer to like elements throughout.

Referring initially to FIGS. 1-4, a portable case 100 according to the present disclosure is now described. The portable case 100 is for carrying a plurality of power accessories. The plurality of power accessories illustratively comprises a plurality of wires 101a-101c, and a charger power block 102 (i.e., an AC/DC adapter block), for example. Of course, other power accessories may be carried by the portable case 100, such as batteries, and cable ties, etc.

The portable case 100 comprises a housing 103 comprising first and second sides 104a-104b, first and second ends 105a-105b extending between the first and second sides, and a plurality of dividing walls 106a-106e extending between the first and second sides, and the first and second ends. The housing 103 may comprise a rigid material of sufficient mechanical strength to resist deformation from typical use;

the rigid material may comprise a plastic polymer material, an acrylic material, a metallic material, or a combination of these materials, for example

The plurality of dividing walls **106a-106e** defines a plurality of compartments **107a-107e**. In the illustrated embodiment, the plurality of dividing walls **106a-106e** are substantially planar in shape and linear in length. The housing **103** also includes a plurality of floor panels respectively within some of the plurality of compartments **107a-107c**. The other compartments **107d-107e** have no floor panel. Although not shown, the opposing side of the housing **103** comprises a symmetrical arrangement of separate opposite side compartments. Since the other compartments **107d-107e** include no floor panel, these compartments are contiguous on both sides of the housing **103**. The plurality of compartments **107a-107e** illustratively includes rectangles-shaped compartments, but it should be appreciated that other shapes are possible in other embodiments.

The portable case **100** illustratively comprises a plurality of aligned slot pairs **110a-110i** carried by the plurality of dividing walls **106a-106e**, and a plurality of spindles **111a-111b**, **112a-112b** respectively received by the plurality of aligned slot pairs. Each slot from the plurality of aligned slot pairs **110a-110i** illustratively comprises parallel ridges extending from adjacent portions of the housing **103**. The plurality of spindles **111a-111b**, **112a-112b** is illustratively configured to receive the plurality of wires **101a-101c**.

In the illustrated embodiment, the floor panel from the first compartment **107a** comprises a plurality of spaced apart slot pairs **113a-113b**, and a plurality of storage openings **108a-108b**. As perhaps best seen in FIG. 1, connection prongs from the charger power block **102** are illustratively received by a respective spaced apart slot pair **113a**. For charger power blocks with integrated cables, the cable may be stowed in the opposite side compartment by threading it through one of the plurality of storage openings **108a-108b**. Also, in some embodiments, the plurality of spaced apart slot pairs **113a-113b** may be compatible with one or more of multiple electrical standards, for example, US and European style plugs. Also, the floor panel from the first compartment **107a** may be removable from the housing **103** and may comprise snap interface tongues (to be received by adjacent portions of the housing) at a periphery thereof. This may allow this compartment to be configurable based upon an application and locale.

The plurality of aligned slot pairs **110a-110i** illustratively comprises a first set of aligned slot pairs **110a-110c** and a second set of aligned slot pairs **110d-110i**. Each first aligned slot pair **110a-110c** is spaced apart a first distance, and each second aligned slot pair **110d-110i** is spaced apart a second distance less than the first distance, thereby receiving different sized spindles. As will be appreciated, the plurality of spindles **111a-111b**, **112a-112b** may comprise different sizes to fit in respective aligned slot pairs **110a-110i** to accommodate varying lengths of wires.

Referring now additionally to FIGS. 5-7, the plurality of spindles **111a-111b**, **112a-112b** illustratively includes a first set of spindles **111a-111b** and a second set of spindles **112a-112b** different from the first set of spindles. Each first spindle **111a-111b** illustratively includes a first spindle body **114** (i.e., an elongate spindle body), a handle portion **115** extending upward from the first spindle body, and a plurality of first spindle slots **116a-116b**, **117a-117d**, **120a-120e** about a periphery of the first spindle body. The plurality of first spindle slots **116a-116b**, **117a-117d**, **120a-120e** illustratively includes a first pair of spindle slots **116a-116b**. In particular, each of the ends of the first spindle body **114** illustratively

includes first and second arms **118a-118b** defining the first pair of spindle slots **116a-116b**. The first pair of spindle slots **116a-116b** are illustratively U-shaped and positioned at opposite ends of the first spindle body **114**. As will be appreciated, the user may grab the handle portion **115** and insert the first and second arms **118a-118b** of a given first spindle **111a-111b** into a given aligned slot pair **110a-110i**. Further, the handle portion **115** comprises a flat upper surface for receiving adhesive labels for identifying a respective wire. In some embodiments, the first spindle body **114** may comprise a medial opening for receiving fastener. For example, the fastener may comprise a suction cup, permitting the user to remove the spindle and wrapped cable and attach it to a wall in a workplace.

The plurality of first spindle slots **116a-116b**, **117a-117d**, **120a-120e** illustratively includes a plurality of second pairs of spindle slots **117a-117d**, **120a-120e** having a different shape than the first pair of spindle slots **116a-116b**. The plurality of second pairs of spindle slots **117a-117d**, **120a-120e** illustratively includes upper slots **117a-117d** flanking the handle portion **115**. Each upper slot **117a-117d** illustratively has a C-shaped inner portion, and a rectangle-shaped outer portion. As shown in FIG. 1, the plug receptacle ends of the plurality of wires **101a-101c** may be tied down via the upper slots **117a-117d**. The plurality of second pairs of spindle slots **117a-117d**, **120a-120e** illustratively includes lower slots **120a-120e** having a U-shape.

Each second spindle **112a-112b** illustratively includes a second spindle body **121**, and a plurality of second spindle slots **122a-122c** extending inwardly from a side of the second spindle body. Each second spindle slot **122a-122c** illustratively comprises a plurality of curved recess pairs. As shown in FIG. 1, shorter length wires may be tied down via the second spindle slot **122a-122c**. Via the plurality of curved recess pairs, several shorter length wires can be fitted into the second spindles **112a-112b**. In the illustrated embodiment, the second set of spindles **112a-112b** are press fitted into the second compartment **107b**. In other embodiments, the portable case **100** may comprise additional aligned slot pairs within the second compartment to hold the second set of spindles **112a-112b**.

Also, the portable case **100** illustratively comprises a cover **123** carried by the first side **104a** and configured to cover the plurality of compartments **107a-107e**, and a handle **124** carried by the second side **104b**. Although not shown, the portable case **100** may comprise another cover for closing the separate opposite side compartments. In some embodiments, the portable case **100** may include a battery testing device **125** carried within a respective compartment (noted with dashed box), and/or a cable testing device **126**. As will be appreciated, the cable testing device **126** may comprise a plurality of wire connector receptables (e.g., USB type A/C port) for receiving wires under test, a plurality of visual indicators configured to generate a pass indicator and a fail indicator. The cable testing device **126** may comprise an auto-off feature activated based upon the state of the cover **123**.

In some embodiments, the portable case **100** has a slimmed down design for reduced weight. In this embodiment, most or all of the plurality of dividing walls **106a-106e** are omitted for a single compartment with boundaries defined by the outer periphery of the housing **103**. Here, the plurality of aligned slot pairs **110a-110i** are carried by the outer periphery of the housing **103**. This embodiment would represent an easy to carry version, in essence comprising compartment **107c** with or without the partial medial wall providing spindle size flexibility.

In some embodiments, the portable case 100 comprises a battery power source configured to power the battery testing device 125. Also, the portable case 100 may comprise integrated lighting (e.g., LED light strips) powered by the battery power source. The integrated lighting may be activated based upon the state of the cover 123. For example, when the cover 123 is opened, the integrated lighting may be activated to aid the user while in dark environments.

Another aspect is directed to a method for making a portable case 100 for a plurality of power accessories comprising a plurality of wires 101a-101c. The method includes forming a housing 103. The housing 103 comprises first and second sides 104a-104b, first and second ends 105a-105b extending between the first and second sides, and a plurality of dividing walls 106a-106e extending between the first and second sides and the first and second ends. The plurality of dividing walls 106a-106e defines a plurality of compartments 107a-107e. The housing 103 further comprises a plurality of floor panels respectively within the plurality of compartments 107a-107e. The method also includes coupling a plurality of aligned slot pairs 110a-110i to be carried by the plurality of dividing walls 106a-106e, and coupling a plurality of spindles 111a-111b, 112a-112b to be respectively received by the plurality of aligned slot pairs, each spindle configured to receive a wire from the plurality of wires 101a-101c.

Helpfully, the portable case 100 may easily store a large number of power accessories. Further, with the plurality of aligned slot pairs 110a-110i, the plurality of spindles 111a-111b, 112a-112b may readily configured depending on the storage needs of the user.

Many modifications and other embodiments of the present disclosure will come to the mind of one skilled in the art having the benefit of the teachings presented in the foregoing descriptions and the associated drawings. Therefore, it is understood that the present disclosure is not to be limited to the specific embodiments disclosed, and that modifications and embodiments are intended to be included within the scope of the appended claims.

The invention claimed is:

1. A portable case for a plurality of power accessories comprising a plurality of wires, the portable case comprising:
  - a housing comprising
    - first and second sides,
    - first and second ends extending between the first and second sides,
    - a plurality of fixed dividing walls extending between at least one of the first and second sides and the first and second ends, the plurality of fixed dividing walls defining a plurality of compartments, and
    - a plurality of floor panels respectively within the plurality of compartments;
    - a plurality of aligned slot pairs carried by the plurality of fixed dividing walls, respective slots from each slot pair being carried on opposite sides of a given compartment;
    - a plurality of spindles, each spindle respectively received by a respective aligned slot pair, each spindle configured to receive a wire from the plurality of wires; and
    - a cover carried by the first side and configured to cover the plurality of compartments.
2. The portable case of claim 1 wherein the plurality of power accessories comprises a charger power block; and wherein at least one floor panel from the plurality of floor

panels comprises a plurality of spaced apart slot pairs, the charger power block to be received by a respective spaced apart slot pair.

3. The portable case of claim 1 wherein the plurality of aligned slot pairs comprises a first set of aligned slot pairs and a second set of aligned slot pairs; wherein each first aligned slot pair is spaced apart a first distance; and wherein each second aligned slot pair is spaced apart a second distance less than the first distance.
10. 4. The portable case of claim 1 wherein the plurality of spindles comprises a first set of spindles and a second set of spindles different from the first set of spindles.
5. The portable case of claim 4 wherein each first spindle comprises a first spindle body, a handle portion extending upward from the first spindle body, and a plurality of first spindle slots about a periphery of the first spindle body.
15. 6. The portable case of claim 5 wherein the plurality of first spindle slots comprises a first pair of spindle slots, and at least one second pair of spindle slots having a different shape than the first pair of spindle slots.
20. 7. The portable case of claim 4 wherein each second spindle comprises a second spindle body, and a plurality of second spindle slots extending inwardly from a side of the second spindle body.
25. 8. The portable case of claim 7 wherein each second spindle slot comprises a plurality of curved recess pairs.
9. The portable case of claim 1 further comprising a battery testing device carried within a respective compartment.
30. 10. The portable case of claim 1 wherein each slot from the plurality of aligned slot pairs comprises ridges extending from adjacent portions of the housing.
35. 11. A method for making a portable case for a plurality of power accessories comprising a plurality of wires, the method comprising:
  - forming a housing comprising
    - first and second sides,
    - first and second ends extending between the first and second sides,
    - a plurality of fixed dividing walls extending between at least one of the first and second sides and the first and second ends, the plurality of fixed dividing walls defining a plurality of compartments, and
    - a plurality of floor panels respectively within the plurality of compartments;
    - forming a plurality of aligned slot pairs to be carried by the plurality of fixed dividing walls, respective slots from each slot pair being carried on opposite sides of a given compartment;
    - coupling a plurality of spindles, each spindle to be respectively received by a respective aligned slot pair, each spindle configured to receive a wire from the plurality of wires; and
    - coupling a cover to be carried by the first side and configured to cover the plurality of compartments.
40. 12. The method of claim 11 wherein the plurality of power accessories comprises a charger power block; and wherein at least one floor panel from the plurality of floor panels comprises a plurality of spaced apart slot pairs, the charger power block to be received by a respective spaced apart slot pair.
45. 13. The method of claim 11 wherein the plurality of aligned slot pairs comprises a first set of aligned slot pairs and a second set of aligned slot pairs; wherein each first aligned slot pair is spaced apart a first distance; and wherein each second aligned slot pair is spaced apart a second distance less than the first distance.

14. A portable case for a plurality of power accessories comprising a plurality of wires and a charger power block, the portable case comprising:

a housing comprising

first and second sides,

first and second ends extending between the first and second sides,

a plurality of fixed dividing walls extending between at least one of the first and second sides and the first and second ends, the plurality of fixed dividing walls defining a plurality of compartments, and

a plurality of floor panels respectively within the plurality of compartments, at least one floor panel from the plurality of floor panels comprising a plurality of spaced apart slot pairs, the charger power block to be received by a respective spaced apart slot pair;

a plurality of aligned slot pairs carried by the plurality of fixed dividing walls, respective slots from each slot pair being carried on opposite sides of a given compartment, each slot from the plurality of aligned slot pairs comprising ridges extending from adjacent portions of the housing;

a plurality of spindles, each spindle respectively received by a respective aligned slot pair, each spindle configured to receive a wire from the plurality of wires;

a battery testing device carried within a respective compartment; and

a cover carried by the first side and configured to cover the plurality of compartments.

15. The portable case of claim 14 wherein the plurality of aligned slot pairs comprises a first set of aligned slot pairs and a second set of aligned slot pairs; wherein each first aligned slot pair is spaced apart a first distance; and wherein each second aligned slot pair is spaced apart a second distance less than the first distance.

16. The portable case of claim 14 wherein the plurality of 10 spindles comprises a first set of spindles and a second set of spindles different from the first set of spindles.

17. The portable case of claim 16 wherein each first spindle comprises a first spindle body, a handle portion extending upward from the first spindle body, and a plurality of 15 first spindle slots about a periphery of the first spindle body.

18. The portable case of claim 17 wherein the plurality of first spindle slots comprises a first pair of spindle slots, and at least one second pair of spindle slots having a different 20 shape than the first pair of spindle slots.

19. The portable case of claim 16 wherein each second spindle comprises a second spindle body, and a plurality of second spindle slots extending inwardly from a side of the second spindle body.

20. The portable case of claim 19 wherein each second spindle slot comprises a plurality of curved recess pairs.
